UNITED STATES PATENT OFFICE.

JOHN LANZ, OF NEW HAVEN, CONNECTICUT, ASSIGNOR TO THE A. C. GILBERT COMPANY, OF NEW HAVEN, CONNECTICUT.

MASSAGE VIBRATOR.

Application filed December 16, 1920. Serial No. 431,185.

To all whom it may concern:

Be it known that I, JOHN LANZ, a citizen of the United States, residing at New Haven, county of New Haven, State of Connecticut, have invented certain new and useful Improvements in Massage Vibrators, of which the following is a full, clear, and exact description.

My invention relates to vibrators, and 10 while the principles thereof may be particularly useful in connection with massage vibrators, such as are frequently used by barbers in giving face massages and also by physicians and others for various purposes, 15 they are equally applicable to a vibrating mechanism of any kind.

The type of vibrator which I have selected to illustrate and describe is one which employs an electromagnet adapted to be used 20 with an alternating pulsating current so that an applicator carrying member is adapted to be attracted toward and released by the magnet. A spring is provided which actuates the applicator carrying member in an 25 opposite direction so that a vibratory movement is obtained. This spring may be conveniently provided as the carrying member of the applicator.

One object of my invention is to simplify 30 and improve the construction of a vibrator of this type and to secure at the same time an improved operation of the same.

Another object of my invention is to provide a vibrator wherein the amplitude of vibration may be adjusted as desired over 35 comparatively wide limits. The adjustment just referred to is obtained without removing the vibrator from the case or without even stopping the operation of the same.

40 A further object of my invention is to provide a vibrator, the parts of which will be a self-contained unit, entirely separate from and independent of the case which encloses the working parts of the same.

45 More specifically, a further object of the invention is to provide a supporting frame to which all of the parts, including the supporting handle of the vibrator, are attached, independently of the enclosing case which is 50 clamped to the supporting frame. The construction thus obtained provides a compact and satisfactory device which is positive and efficient in operation, and which is pleasing in appearance and of light weight, so that it 55 may be easily carried in the hand.

In the accompanying drawings:

Fig. 1 is a side elevation of a vibrator, embodying my improvements;

Fig. 2 is a sectional view of the same, showing the working parts of the vibrating 60 mechanism;

Fig. 3 is a front view of the vibrating mechanism with the applicator and the enclosing case removed; and

Fig. 4 is a rear view of the vibrating 65 mechanism with the applicator and the enclosing case removed.

The vibrator which I have selected to illustrate and describe is one which embodies the principles of my invention, consisting of an applicator 10, a vibrating mechanism 11, a supporting handle 12 and an enclosing case 13. The vibrating mechanism comprises a supporting frame 14, to which, it will be observed, all of the parts 70 of the vibrator are attached. The supporting frame is provided at its lower portion with a threaded opening 15, which is adapted to receive a threaded stem 16 upon the supporting handle. At the junction of this 75 threaded stem with the supporting handle 12, a shoulder 17 is provided upon the handle. The case 13 is provided with a main body portion 19 and a front cap portion 20, which is removably attached to the body 80 portion. This attachment is secured by providing L-shaped recesses 21 in the edge of the body portion, providing bosses 22 in the edge of the cap portion which are adapted to be received in the recesses 21, and then 85 the cap may be rotated to locking position. The body portion 19 of the cap is provided with an opening 23 at its lower portion, through which the threaded stem 16 of the handle is adapted to extend, and in this manner, the case may be firmly clamped to the supporting frame when the stem 16 is received in this socket 15, by being clamped between the shoulder 17 and the lower base 90 of the frame. Some packing 24 which may 100 be in the form of a piece of fibre or the like may be placed between the case and the lower portion of the base 14 so as to prevent any looseness of the case when the handle is screwed into position.

105 The operating mechanism for the vibrator is secured upon the case 14 by two screws or bolts 25, which pass through a U-shaped soft iron core 27 of an electromagnet. A spacing sleeve 26 is placed upon each of the bolts 25 110

and serves to hold the soft iron core at the outer end of these bolts in proper position relative to the associated parts. Upon each leg of the U-shaped core is placed a coil 28, 5 which coils are connected in series in the usual way and supplied, in the embodiment shown, with an alternating current through the wires 29. It will be apparent that the principles of this invention may be applicable also to a vibrator with which a direct current is used, although I have chosen to show a simple form of vibrator operated by an alternating current.

The applicator 10 is carried upon a member 30 which, in the embodiment illustrated, is shown as a resilient or spring member secured to the supporting frame at 31 and provided with a body portion which passes over the poles of the magnet and has a down-turned end to which the applicator is secured. A threaded socket member 32 is secured to the down-turned end of this carrying spring, and the applicator is secured upon a threaded stem 33, which is received 20 in this socket member. A soft iron armature 34 is secured to the carrying member at a point above the poles of the electromagnet so that when the magnet is energized by the current supplied through the wires 29, the carrying member will be attracted 25 toward the same. It is seen that with the use of an alternating current, this attraction will be only momentary, and when the soft iron armature is released, the resilience of the carrying member will serve to actuate it in a direction away from the magnet, from 30 which position it will again be attracted when the magnet is energized by the current. It is thus seen that an efficient and positive 35 vibrating operation of the applicator will be obtained. It will be apparent, of course, that the applicator carrying member might be pivotally connected to the supporting frame and a separate spring provided to actuate it 40 in a direction away from the magnets, without departing from the principles of my invention in some of its aspects.

Provision is made for adjusting the tension of the spring carrying member in this 50 case, so that an adjustment of the degree of vibratory movement of the carrying arm and applicator is obtained. A second spring 55 is in the form of a flat resilient member 35 secured to the carrying member 30, preferably to an intermediate portion of the same, and in the form shown, it is connected to a portion of the carrying member which is opposite the soft iron armature. This 60 spring member 35 extends rearwardly and is provided with a down-turned portion 36, which is slotted at its lower end as at 37, and which may be held in adjusted positions 65 with respect to the frame 14 by an adjusting screw 38, provided with a threaded portion 39, which may be screwed into the frame

member 14 and also provided with a shoulder portion 40 which is adapted to bear against the edges of the slot 37 to force the portion 36 of the spring 35 toward the frame, thus tending to raise the carrying member 30 from the poles of the magnet and to increase the tension of the same. It will be apparent that the opposite movement of the screw will allow the carrying member 30 to approach the poles of the magnet and will relieve the tension of the carrying member. Thus a very satisfactory provision for adjusting the degree of vibratory movement of the applicator is obtained.

It is observed that all of the working parts 80 of applicant's vibrator are attached to the supporting member 14 and are entirely separate from and independent of the case 13. The vibrating mechanism, consisting of the frame 14, and the operating mechanism, 85 which is the electromagnet, the applicator carrying member 30, the tensioning spring member 35, the adjusting screw 38, all of which are secured to this frame 14, together with the supporting handle 12 and the applicator 10, constitute a unit, the parts of which in no way depend upon the case for their support or connections. The adjustment of the degree of vibratory movement 90 may be accomplished without removing the case or without stopping the operation of the applicator. By unscrewing the supporting handle 12, the applicator 10 and the adjusting screw 38, the front cap of the case 95 may be removed and the vibrating mechanism as a whole removed from the case. The parts may, of course, be re-assembled independently of the case, and the operation 100 will be just as efficient.

While I have shown and described my invention as applied to a massage vibrator, it will be apparent that the invention is not limited to the exact details of the drawing, but is capable of many modifications and variations which will fall within the spirit 110 of the invention and the scope of the appended claims.

What I claim is:

1. A vibrator comprising a casing, a frame within said casing, a flat resilient member 115 connected at one end to the frame, and carrying an applicator at its free end, a second flat resilient member connected at one end to said first member and having its other end adjustably connected to the frame, and actuating mechanism for the applicator carried by the frame.

2. In a vibrator, a frame member having a base portion adapted to be secured to a handle member, and an arm portion generally at right angles to said base portion, an electro-magnet secured to said arm portion and extending parallel therewith, a resilient applicator supporting member secured to the upper end of said arm portion and ex- 130

- tending over the upper poles of said electro-magnet, and having a portion turned downwardly parallel with said arm portion, said downwardly turned portion being adapted 5 to carry a massage applicator, said supporting member having a magnet armature secured thereto at the portion thereof directly over said magnet poles and being tensioned to retain said armature out of contact with 10 said poles, another resilient member secured to the first, said second resilient member extending downwardly, spaced from and parallel with said arm portion of said frame, and means to press the free end of said 15 second resilient member toward said frame whereby additional tension may be supplied to and relieved from said first mentioned resilient member to vary the vibrations caused by the attraction between the magnet 20 poles and the armature.
3. In a vibrator, a frame member having a base portion provided with an arm portion extending upwardly therefrom, a supporting and operating member extending horizontally from the upper end of said frame arm portion and having a depending portion provided with means for connection with a device to be vibrated, means secured to said frame member for causing vibrations in 25 said operating member, and means secured to said operating member and adjustable relatively to said frame member for controlling the tension of said operating member to vary the amplitude of the vibrations 30 thereof, said operating member tension controlling means and said connecting means for the device to be vibrated extending in opposite directions from said frame member.
4. In a vibrator, a casing, a frame member comprising a base portion and an arm portion, an electro-magnet mounted thereon and therebetween, a resilient vibrating member secured to the arm of said frame and extending over the poles of said electro-magnet for vibration thereby, said member having a depending portion adapted for engagement with a device to be vibrated, another resilient member secured to the first mentioned one, said second mentioned resilient member having a depending portion substantially parallel to and spaced from said frame arm, and means engaging said frame and operating upon said second mentioned resilient member to alter the tension 50 of said first mentioned resilient member, whereby the amplitude of vibrations thereof is controllable.
5. In a vibrator, a casing, a handle, a frame member attached thereto within said casing having a generally longitudinal arm portion, a flat springable member having a transverse portion, one end secured to the upper end of said arm portion and turned at right angles to said arm portion and extending 55 forwardly parallel with said base por-
- tion, said member also having an integral portion depending from the forwardly extending portion, adapted for connection with a device to be vibrated, and an electro-magnet secured to said frame between said 70 depending member portion and said frame arm portion and positioned to act upon an armature part of said forwardly extending portion of said flat member.
6. In a vibrator, a vibrating unit comprising an L-shaped supporting frame member, an electro-magnet secured thereto, a combined armature spring and applicator supporting member, said member being secured at one end to the arm of said L-shaped member and extending over the poles of said magnet, having means at its free end to be connected to an applicator, and a casing about said unit, a vibration controlling spring member secured to said combined armature spring and applicator supporting member, means cooperating with said frame member and acting against said vibration controlling member whereby the amplitude of vibrations may be varied, said means for connecting said combined armature spring and applicator support with an applicator, and said means for acting against said vibration controlling means, extending without the casing in opposite 85 directions.
7. In a vibrator, a handle, a frame member attached thereto having a generally longitudinal arm portion, a longitudinally extending electro-magnet, and a flat springable transversely extending member having an end portion secured to said arm portion of said frame member, the other end portion being turned downwardly and adapted to be connected with a device to be vibrated, said springable member being operatively positioned above said magnet and adapted to be attracted thereby whereby vibrations are caused in said downwardly turned portion when said magnet is energized.
8. In a vibrator, a handle, a frame member attached thereto having a generally longitudinal arm portion, a longitudinally extending electro-magnet, a support for said electro-magnet secured to said arm portion and extending transversely therefrom, and a flat springable transversely extending member having an end portion secured to said arm portion of said frame member, the other end portion being turned downwardly and adapted to be connected with a device to be vibrated, said springable member being operatively positioned above said magnet and adapted to be attracted thereby whereby vibrations are caused in said downwardly turned portion when said magnet is energized.
9. In a vibrator, a handle, a frame member attached thereto, having a transversely extending base portion adapted to be en-

gaged by said handle and having a generally longitudinally extending arm portion, a longitudinally extending electro-magnet, a support for said electro-magnet secured to said arm portion and extending transversely therefrom, and a flat springable transversely extending member having an end portion secured to said arm portion of said frame member, the other end portion being turned 10 downwardly and adapted to be connected

with a device to be vibrated, said springable member being operatively positioned above said magnet and adapted to be attracted thereby whereby vibrations are caused in said downwardly turned portion when said magnet is energized.

In witness whereof, I have hereunto set my hand on the 11th day of December, 1920.

JOHN LANZ.
